UNITED STATES PATENT OFFICE.

PHINEAS F. KING, OF CLEVELAND, OHIO, ASSIGNOR OF ONE-HALF TO
CHARLES H. TUCKER, OF CLEVELAND, OHIO.

TROLLEY-POLE.

SPECIFICATION forming part of Letters Patent No. 740,144, dated September 29, 1903.

Application filed August 23, 1902. Serial No. 120,830. (No model.)

To all whom it may concern:

Be it known that I, PHINEAS F. KING, a citizen of the United States, residing at Cleveland, in the county of Cuyahoga, State of Ohio, have invented certain new and useful Improvements in Trolley-Poles; and I do hereby declare that the following is a full, clear, and exact description thereof.

My invention relates to trolley-poles used on electric-railway cars; and the object of the invention is to provide a trolley-pole so constructed that when in operation there will be a constant and equal pressure of the trolley-wheel on the overhead wire, and should said wheel become disengaged from the wire (which frequently happens) the pole will remain in substantially the position it is in when said wheel leaves the wire and at the same time readily admit of its being brought into contact adjustment with the wire by the conductor in the ordinary manner.

With these objects in view the invention consists of the construction and combination of the parts hereinafter described, and pointed out definitely in the claims.

In the drawings forming a part of this specification, Figure I is a side elevation of a portion of a car, showing the improved trolley-pole attached thereto, with the wheel in contact with the overhead wire. Fig. II is a side elevation of the improved pole detached. Fig. III is a front elevation of the same. Fig. IV is a detail view of the lower end of the pole, showing a cam thereon, which is a preferable form of construction, as will be fully explained farther on. Fig. V illustrates a modified construction. Fig. VI shows another modified construction wherein the ordinary spiral spring now in use is applied.

Similar letters of reference designate similar parts in drawings and specification.

It is well known to all familiar with electric railways employing the overhead system that a great amount of damage is caused by the trolley-wheel leaving the wire and under pressure of the spring throwing the pole into a perpendicular position and causing said pole to come into contact with the cross-wires or other obstacles, and thereby either bend and distort the pole or break said cross-wires, causing danger to the public from the falling

of the overhead wires and a blocking of the cars on the line necessitated by the breaking of the supporting-wires.

It will be readily understood from the following description of my invention that these undesirable features of the overhead-trolley system are practically eliminated.

In the drawings, A represents a railway-car of the ordinary type.

B is a housing pivotally connected to the plate C, which is secured to the roof of the car. In the preferred form of construction (shown in Figs. I, II, and III) the housing B is provided with two segmental racks b and the trolley-pole D is pivoted in said housing at d, the center of the segmental racks.

E represents a pawl pivoted to the trolley-pole at e and adapted to engage the two segmental racks b under pressure of the spring f. Extending forward from the housing B is an arm G, to which is attached a flat spring g, the free end of which bears on the under side of a cam-foot d' of the trolley-pole. The arm G is rigid with the housing B, and therefore is free to revolve therewith. The upper portion D² of the trolley-pole is connected with the lower portion at d² by a knuckle-joint and is provided with an arm d³, thereby forming a bell-crank lever. A rod i connects the arm d³ with the rear end e' of the pawl E. The adjusting-cord H is attached to the pawl E at e² forward of the pole D and passes over a pulley d⁴ on the upper portion D² of the pole and from thence down to the rear of the car, the same as the ordinary trolley-cord.

I have now described the preferred construction of the improved trolley-pole and will proceed to explain the operation of same, following with a description of the modified forms embodying the same general principle.

In the construction hereinbefore described the trolley-wheel w under pressure of the spring f on the cam-foot of the trolley-pole is kept in contact with the wire t, said pressure causing the pawl E to be disengaged from the segmental racks through the action of the bell-crank lever and the rod i. Now should the trolley-wheel leave the wire the spring s immediately causes the forward end of the pawl E to disengage the teeth of the rack b, and thereby hold the pole in sub-

stantially the position it is in when the wheel leaves the wire. The trolley-wheel *w* cannot leave the wire *t* unless it is for some cause or other thrown down a greater distance than 5 the depth of the groove in said wheel, in which case the counteracting pressure of the trolley-wire on said wheel is removed and the pawl *E* will engage the rack *b* and hold the pole below the trolley-wire, and should 10 said pole come in contact with any obstacle below the wire the pole is forced farther down and the pawl engages the rack in a lower position, retaining and preventing said pole from assuming an upright position until 15 the pawl is released from the rack by the cord *H*, when the trolley-wheel can be freely brought into contact with the wire in the ordinary manner.

It will readily be seen that while the wheel 20 *w* is in contact with the overhead wire the pawl is out of engagement with segmental rack, and said wheel under pressure of the spring *g* is free to follow in contact with said wire throughout all its undulations.

25 The foregoing-described construction is the preferable form, as the flat spring *g* maintains a positive and equal pressure on the trolley-wheel on the trolley-wire at all angles.

30 In Figs. V and VI, I have illustrated modified forms of construction embodying the same general principle.

In Fig. V a serrated rack *b* is used, and a serrated cam *E* is adapted to engage therewith.

35 Fig. VI illustrates the device with the ordinary spiral spring in common use connected therewith. The invention will admit of other minor differences in details of construction without departing from the nature and scope of the invention—as, for example, the placing of the rack on the interior of the segment and adjusting the pawl so that it will engage therewith.

40 Having now described my invention, what I claim, and desire to secure by Letters Patent, is—

1. In a trolley-pole in combination with a revolving frame, provided with a ratchet-45 segment, a pole pivoted in said frame, a pawl pivoted to said pole and arranged to engage said segment, said pole consisting of two por-

tions hinged together, a rearwardly-extending arm rigidly secured to the upper portion, a rod connecting said arm and said pawl 55 whereby said pawl may be thrown out of engagement with said segment when the upper portion of said trolley is operated upon its hinge, and a spring tending to throw said pawl into engagement with said segment. 60

2. A trolley-pole pivoted in a frame attached to the car, a spring-pawl pivoted to said trolley-pole and adapted to engage segmental racks, said segmental racks to be a part of said frame and having their radial centers at the pivotal point of the trolley-pole, the upper portion of the trolley-pole being in the form of a bell-crank lever and hinged to the lower portion, the upper arm of said bell-crank lever carrying the trolley-wheel and the lower arm extending rearwardly and connected by a rod with the rear of the pawl whereby rearward motion of the upper portion of the trolley-pole will disengage the pawl from the segmental rack, a 75 spring acting on said trolley-pole whereby contact-pressure is maintained between the trolley-wheel and the trolley-wire, and means for releasing the pawl from the rack independently of the bell-crank lever, substantially 80 as described.

3. In a trolley-pole the combination of the pole proper, made up of two sections hinged together, the upper section being in the form of a bell-crank lever, a frame swiveled to the 85 top of the car, two segmental racks carried by said frame, the trolley-pole pivoted at the radial centers of said racks, a pawl pivoted to the pole and adapted, under spring-pressure to engage said racks, a rod connecting 90 the free arm of the bell-crank lever with the rear of the pawl, a cord connected with the front end of the pawl and passing over a pulley on said pole and a spring acting on the lower end of the pole whereby the wheel is 95 kept in contact with the trolley-wire, substantially as described.

In testimony whereof I affix my signature in presence of two witnesses.

PHINEAS F. KING.
